SLUG CASTING MACHINE

Joseph F. Krusberger, Brooklyn, N. Y., assignor
to Mergenthaler Linotype Company, a corpora-
tion of New York

Application September 20, 1949, Serial No. 116,700

8 Claims. (Cl. 199—50)

1

This invention relates to slug casting machines, such as Linotype machines of the general organization represented in United States Letters Patent to O. Mergenthaler No. 436,532, wherein circulating matrices and expansible spacebands are composed in line by the manipulation of a keyboard, the composed line transferred to a slotted mold for the casting of a type bar or slug, and the matrices and spacebands thereafter separated and returned by a distributing mechanism to the magazines from which they started. More particularly, the invention relates to machines of this character equipped with quadding and centering devices, in order that the machine may handle not only lines of full length as ordinarily, but in addition lines of less than full length (regardless of their actual length), lines of the latter kind in machines of this character being composed merely with the matrices necessary for the printed matter and indented at the left or at the right end of the line or centered as desired.

A machine so constructed is disclosed in the Frolander Patent No. 1,971,400, dated August 28, 1934. In the machine therein disclosed the movable supports for the two line clamping jaws (the latter being made long enough to perform their required functions of closing the mold slot at the front) are actuated through two distinct trains of connections from a vertically movable member controlled from the main shaft of the machine. When both jaw supports are connected to the member, they are, prior to casting, moved equidistantly toward each other until arrested by the contact of their respective jaws with the opposite ends of the composed line (for centering) and later, after casting, restored to their original positions of maximum separation. Due provision is made for disconnecting either the right-hand jaw or the left-hand jaw from the vertically movable member, so that one or the other may be operated independently for quadding at the right or at the left as may be desired. When both jaws are disconnected, as they may be, the machine is free to function in the usual way, the right-hand jaw being left normally stationary and the left-hand jaw being adjustable by the customary devices. When the clamping jaws are moved into contact with the composed line, the vertically movable member is locked in its downwardly moved position by means of a toggle clamp actuated by a lost motion device included in the operating connections and, after a casting operation, the toggle clamp is released, allowing the vertically movable member

5 to ascend and restore the clamping jaws to their positions of maximum separation.

An improvement upon the aforementioned toggle clamp is disclosed in the Mead Patent No. 2,092,220, dated September 7, 1937, wherein the grip element is allowed a limited degree of movement while still in engagement with the vertically movable member to allow the latter to be actuated upwardly for a small distance to permit the slight backing off of the line clamping jaws before the line has been lifted clear of the jaws, the grip element later (after the line has cleared the jaws) being disengaged from the vertically movable member to permit it to ascend to its uppermost position and return the jaws to their positions of maximum separation.

The disclosures of the Frolander and Mead patents referred to, contemplate the closing of the jaws against the composed line under pressure and thereafter effecting a positive separation of the jaws for a limited distance for the free expansion of the spacebands in justifying the line, the justification pressure being sufficient (as in regular machine operation) to spread out the line tightly between the jaws. It is not the practice, however, to justify quadded lines, whether or not they contain spacebands, except in certain instances such as for so-called straight-line indentation, when the jaws are backed off from line contacting position to abut against fixed stops. In the absence of justification, the line closing pressure of the jaws is not always great enough to compress the matrices in the line sufficiently to prevent metal squirts or the production of hair lines on the cast slug. For example, the line clamping jaws are supported loosely enough so that under normal line closing pressure they may contact the end matrices of the line in a tilted position and thus fail to engage the matrices throughout their full height. This leaves a space at one or both ends of the line between the end matrices and the matrix engaging faces of the jaws through which metal can squirt when injected into the mold for casting. The other difficulty, the production of hair lines on the slugs, may be due to several causes, chief among which is that arising from the fact that as a result of continued use the matrices warp or otherwise become bent, or in the case of the thinner matrices they may not be straight even when new, and, hence, they do not stand in side-wise contact throughout their full extent when composed in line and must be compressed into tight engagement. If this were true of one or two matrices only, the line closing pressure might

squeeze the line sufficiently to straighten the matrices, but when one-half or more of the total number of matrices in the line must be straightened to obtain a tight lock-up, as is frequently the case, the line closing pressure may be far from adequate.

To obviate this condition, it has been proposed (see Hilpman Patent No. 2,255,254) to move the jaw (assuming one jaw only to be connected for movement) into line contacting position for quadding as usual, and then apply a supplemental pressure through the jaw moving means to urge the jaw inwardly from its line contacting position to squeeze the line tight enough to insure the straightening and complete sidewise contact of all matrices composed therein. Such line squeezing pressure also serves to straighten the jaws so that their matrix engaging faces make complete contact with the side faces of the end matrices.

It is the object of the present invention to improve upon the quadding and centering devices of the earlier patents cited, with the idea of simplifying the mechanism heretofore employed in performing the various functions mentioned and of rendering the quadding and centering operations more effective. These improvements will best be understood from the detailed description to follow.

Referring to the drawings:

Fig. 1 is a front elevation of the casting mechanism of a Linotype machine, equipped with the present improvements, certain portions being broken away and other portions shown in section to reveal structural details;

Fig. 2 is a vertical section taken on the line 2—2 of Fig. 1;

Fig. 3 is an end elevation (taken from the left in Fig. 1) of the quadding and centering mechanism as shown in normal position and set for a quadding operation;

Fig. 4 is a front elevation of the parts shown in Fig. 3;

Fig. 5 is a horizontal section taken on the line 5—5 of Fig. 4;

Fig. 6 is a vertical section taken through the locking devices for the jaw operating rod and showing said devices disengaged therefrom;

Fig. 7 is a similar section but showing the locking devices engaged with the rod in one position thereof;

Fig. 8 is a view similar to that of Fig. 7 but showing the locking devices engaged with the rod in a different position thereof; and

Fig. 9 is a horizontal section taken on the line 9—9 of Fig. 8.

The matrices 1 and the expandable spacebands 2 are composed in line in an assembler in the usual way and transferred to a vertically movable transporter or first elevator 3, which thereupon descends to position the line between the left-hand jaw 4 and the right-hand jaw 5 (see Figs. 1 and 2) and in front of a slotted mold 6 indicated by the dotted lines in Fig. 2. The mold then advances from the rear into contact with the line and with the two jaws for the slug casting operation, the line, prior to casting, being aligned and justified in the same manner as when the machine is being operated under the usual conditions. Thereafter, the mouthpiece of a melting pot (not shown) is advanced from the rear into contact with the rear face of the mold and molten metal then injected into the mold for the casting of the slug against the composed line. After the slug has been cast, the melting

pot is moved rearwardly out of contact with the mold and the latter likewise moved rearwardly out of contact with the composed line, whereupon the mold is carried around from its horizontal casting position to a vertical ejecting position by a three-quarter rotation of the mold disk 7, the first elevator in the meantime being raised to deliver the composed line to the matrix and spaceband distributing devices and finally coming to rest in its original or line receiving position.

For movement to and from casting position, the melting pot is mounted upon a pair of supporting arms 8 (only one of which is shown in the drawings) pivoted at their lower ends upon a transverse rod 9 in the fixed vise frame 10.

As more fully shown and described in the Frolander patent above referred to, the two jaws 4 and 5 are mounted for movement in the vise frame in the customary manner, being carried by supporting blocks slideable in suitable guideways formed in the vise frame, and are movable toward and from each other by a periodically operated part in the form of a vertically movable rod 11 which may be connected at its upper end to the respective jaws through the medium of two small but oppositely disposed bell crank levers 12 and 13 pivoted at 14 and 15 to the vise frame, the longer arms of said levers being connected by short links 16 and 17 to the supporting blocks for the respective jaws, and the shorter arms of said levers being arranged for connection to or disconnection from the rod 11. According to this arrangement, when the rod 11 is moved downwardly from its uppermost position (which is its normal position of rest), it will move the two jaws equidistantly toward each other (assuming both to be connected to the rod) until they contact with the opposite ends of the composed line which has previously been positioned between them, and when the rod is moved upwardly for restoration to its position of rest, it will in like manner move the jaws equidistantly away from each other to return them to their original positions of maximum separation. Since the composed lines positioned between the jaws may vary in length, the actual extent of movement of the rod 11 will of course vary accordingly and hence provision is made for such varied movement of the rod in its actuating connections in the usual way.

As also more fully shown and described in the Frolander patent, a suitable device in the nature of a segmental grooved member 18 is provided at the upper end of the rod 11 for connecting the jaws thereto, this grooved member being adjustable by a handle 19 through a rack and pinion arrangement 20 so as selectively to connect either or both of the jaws to the rod as desired for quadding at either end of the line or for centering. A second handle 21, pivoted at 22, and operatively connected with a coupling pin 23 associated with the grooved member 18, serves to disconnect the rod 11 from both jaw operating levers for a regular machine operation. The two handles, through their actuating connection, thus constitute means for conditioning the machine for a quadding or regular machine operation, as may be desired.

The rod 11 is slideable in upper and lower bearings in the vise frame and is operated through a train of connections, indicated generally by the reference numeral 26, from an edge cam (not shown) fast to the main shaft of the machine. This cam, which makes one complete rotation at

5.

each cycle of operation of the machine, acts to move the rod first downwardly to effect the inward or closing movement of the jaws and then upwardly to effect the outward or separating movement of the jaws.

The justification of the composed line is effected in the usual way by a two-stage upward thrust of the bar 27 against lower ends of the longer or pendant wedge sections of the spacebands to force them upwardly between the matrices and to expand the line between the clamping jaws. The bar 27 is carried at the upper ends of two spaced vertical rods 28 and 29 slidable in upper and lower bearings in the vise frame. Between the bearings, the rods are formed with collars 30 and 31, respectively, and the ends of the two justification levers (one lever 32 only being shown) engage the collars from below in raising the rods successively during justification. When spacebands are present in the composed line, they will limit the extent to which the justification bar can rise, but if the line is composed without spacebands, the bar is free to partake of a full stroke, the upper limit of which is determined by the banking of the upper ends of the collars 30 and 31 against the upper bearings for the respective rods 28 and 29.

As thus far described, the parts and their mode of operation, except as hereinafter noted, are or may be the same as set forth in the aforementioned patents, see in particular the Hilpman Patent No. 2,255,254, which discloses what was at the time the most modern development of the quadding and centering device in use on commercial machines.

Coming now to the present improvements:

A new form of locking device is provided to hold the rod 11 in its downwardly moved position during a quadding or centering operation. This locking device comprises a plurality of pawls or detents 40 (four shown by way of example) disposed horizontally one upon another in vertical stack formation and enclosed within a box or cage 41. The detents are each formed at their rear ends with a series of uniformly spaced rack teeth for engagement with similar but oppositely disposed rack teeth 42 formed directly in the rod 11. The teeth 42 extend practically throughout the length of the rod 11 or, in any event, for a distance equal to the full extent of movement of the rod for quadding or centering. The spacing of the teeth on both the rod and detents is of the order of .084", which enables the teeth to be made strong enough to resist shearing under the heavy line squeezing pressure (later to be described) which is applied through the rod. Such wide spacing of the teeth is permitted by arranging the teeth on the detents in stepped or staggered relation as between the detents, such stepping or staggering being of the order of .021" and thus insuring engagement of at least one of the detents with the rod in any given position of the rod within that small dimension. This is clearly depicted in Figs. 7 and 8, which show the first and third detents (counting from the top) fully engaged with the rod in slightly different positions thereof. As will be evident from the drawing, the rack teeth of both the rod and detents are bevelled to facilitate their mutual engagement, this beveling acting (if need be) to depress the detents as a unit (as permitted by the mounting later to be described) in insuring full engagement of the teeth in any position of the rod.

The box or cage 41 presents a bottom wall 41a

6.

upon which the detents are supported, a front wall 41b formed with rows of holes or perforations to receive the protruding ends of spring-pressed plungers 41c which constantly press rearwardly on the detents, side walls 41d which guide the detents at their opposite edges in their forward and rearward movements, and two rear flanges 41e which engage shoulders formed at the rear ends of the detents and which limit the rearward movement of the detents under the influence of the spring-pressed plungers. Normally, or when the locking mechanism is inactive, the cage 41 is held forwardly in the position shown in Fig. 6, with all the detents in alignment and with their teeth clear of the teeth on the rod 11. However, when the locking mechanism is operated, the cage 41 is pushed rearwardly to engage one or another of the detents with the rod 11, that particular detent being the one whose teeth will accurately mesh with the rack teeth on the rod and the others (whose teeth do not so mesh) being permitted to yield with reference to the cage (see Figs. 7 and 8).

The cage 41 is mounted for such backward and forward movements in a housing 43 which contains the upper bearing 25 for the rod 11. At its forward end, the housing 43 is provided with a fixed nut 44 into which is threaded a short rotatable screw 45 formed at its rear end with a grooved stem portion which makes a swivel connection to a plate 46 attached to the cage 41 (see Figs. 6 to 9). As will be evident from the drawings, when the screw is rotated in one direction the cage 41 will be forced rearwardly to engage the detents with the rod 11, whereas when the screw is rotated in the opposite direction the cage will be drawn forwardly to disengage the detents from the rod.

Instead of being operated by the jaw moving mechanism, as in the prior patents mentioned, the new locking mechanism is operated by independent mechanism which, in the preferred embodiment illustrated, includes two sets of connections, one set actuated by the melting pot as it is swung into casting position and which effects the locking action before casting, and the other set actuated by the first elevator as it is moved upwardly from casting position and which effects the unlocking action after casting.

Referring first to the pot actuated connections: Pinned to the forward end of the screw 45 is a double-armed lever 50 having one arm connected by a bent vertically disposed link 51 to the free end of a bent arm 52 extending forwardly from one end of a short transverse rock shaft 53 journaled in a fixed bracket 54 attached to the vise frame. Extending downwardly from the opposite end of the rock shaft 53 is a right angular arm 55 formed at its free end with a laterally projecting plate 56 contacted by a roller 57 journaled in the lower end of an arm 58 pivotally suspended, as at 58a, from the justification locking lever 104 later to be described. When the machine is conditioned for a quadding or centering operation, as depicted by the full lines in the drawings, the arm 58 will stand in front of and be engaged by a spring-pressed plunger 59 mounted in a bracket 60 clamped, as at 61, to one of the pot supporting legs 8. Consequently, when the melting pot is swung forward to casting position, the plunger 59 will move the parts from the full line position shown in Fig. 3 to the dotted line position shown therein, lifting the link 51 and turning the lever 50 in a clockwise direction as viewed from the front (see dotted lines in Fig. 4), thus imparting

a similar rotation to the screw 45 and causing the latter to engage the locking detents with the vertically movable rod 11.

A long off-center tension spring 62 is employed to hold the parts in one position or the other. This spring is anchored at its upper end to a pin 63 projecting laterally from the supporting bracket 54 and is attached at its lower end to a pin 64 projecting laterally from the free end of an arm 65 depending from the rock shaft 53 behind the arm 52. As will be noted in Fig. 3, when the parts are in their normal position, as shown by the full lines, the spring 62 will be disposed rearwardly of the axis of the rock shaft 53, but when the parts are in their operative position, as shown by the dotted lines, the spring will be disposed forwardly of the axis of the rock shaft. The extent of movement of the pot actuated plunger 59, therefore, need only be sufficient to move the spring 62 past dead center, the spring thereafter having sufficient force to complete the movement of the parts. In this connection, it is pointed out that a stop pin 66 located on the fixed housing 43 (see Fig. 4) limits the turning movement of the screw operating lever 50 in one direction, while a stop lug 51^a, carried by the link 51 and arranged to bank upon the upper surface of the housing (see Fig. 3), limits the turning movement of said lever in the opposite direction.

Referring now to the connections actuated by the first elevator: Projecting forwardly from the screw turning lever 50, in overhanging relation thereto, is a cam plate 70 formed on the upper end of the arm opposite that to which the lifting link 51 is attached. To cooperate with the cam plate, the first elevator is provided with a small rocking lever 71 pivoted to the elevator at 72 and held normally in horizontal position by a spring 73 and set screw 14. At the rear, the lever is formed with an upstanding bevelled finger 75 which is arranged to engage the under face of the cam plate 70 when the screw turning lever occupies the position indicated by the dotted lines in Fig. 4, which position is the one to which the lever will be turned by the pot actuated connections in engaging the locking detents 40 with the vertically movable rod 11 before casting. After casting, when the first elevator moves upwardly to lift the composed line from between the jaws for distribution, the finger 75, by its engagement with the cam plate 70, will rock the screw turning lever 50 back to its original position and thus effect the disengagement of the locking detents from the vertically movable rod. This reverse rotation of the screw turning lever is timed to take place before the composed line has moved entirely clear of the clamping jaws, the purpose being to delay the disengagement of the locking detents from the rod until after the latter, in the manner presently to be described, is allowed to rise slightly in releasing the pressure of the jaws on the composed line. It may be explained that the pivotal mounting of the lever 71, while perhaps unnecessary, is intended to permit it to rock out of the way of the cam plate 70 during the downward movement of the first elevator in the event that the cam plate at such time stands in the path of the finger 75.

Like the single locking detent of the Hilpman patent several times referred to, the locking detents 40 of the present invention are mounted in the housing 43 not only for a rearward and forward movement, as above described, but also for a limited vertical or upward and downward movement with reference thereto, it being noted

that the grooved stem portion of the screw 45 is designed to permit such upward and downward movements without breaking its swivel connection with the cage 41. Normally, the cage 41 is held in its upward position within the housing by means of a hollow plunger 80 located in a recess formed in the bottom wall of the housing 43 and constantly pressed upwardly by a spring 81 contained within the plunger, all as clearly shown in Figs. 6 to 8. As a matter of convenience in making adjustments or repairs, the plunger 80 is provided with a handle 82 extending downwardly through an opening in the bottom wall of the housing.

The downward movement of the locking detents is effected after they have been engaged with the vertically movable rod 11 and consequently is imparted to said rod in order to force the clamping jaws inward from their line contacting positions to squeeze the line before the casting operation. The mechanism employed for the purpose is substantially the same as that more fully shown and described in said Hilpman patent, comprising a fore-and-aft slide 90 having a pin and slot connection 91 with the housing 43 at one side thereof (Figs. 3 and 4). The rear end of the slide 90 is hook-shaped to cooperate with a hooked plate 92 carried by a spring-actuated link 93 controlled by a cam (not shown) on the main cam shaft of the machine. At its forward end, the slide 90 is bent to provide a lip 94 arranged to engage in front of a cam arm 95 pivotally suspended from the free end of a lever 96 pivoted at 97 to the housing 43 at the side opposite that on which the slide 90 is located. The lever 96 overlies the housing 43 and is formed with a lug which passes through the top of the housing and bears upon the uppermost detent 40. The cam arm 95 engages a roller 98 mounted on a fixed pin between the housing and a strap 99 which holds the arm against sidewise movement. According to this arrangement, when the slide 90 is moved rearwardly by the link 93 (which is actuated by a powerful spring), the lip 94 engages and rocks the cam arm 95 which, by its engagement with the roller 98, draws the lever 96 downwardly to apply the full downward pressure of the actuating connections to the locking detents 40 and through them to the rod 11. After the casting operation, and when the operating link 93 is restored to its original position under cam control, a spring 100 exercises itself to draw the slide 90 forward and allow the cam arm 95 to rock back to its original position as the lever 96 is raised by the locking detents 40 in response to the upward pressure of the spring plunger 80. It is this upward movement of the locking detents which releases the pressure on the composed line while they are still engaged with the rod 11 and before the first elevator lifts the line from between the clamping jaws. For a more detailed description of this line squeeze action, reference may be had to the Hilpman patent.

According to the present improvements, when the composed line is quadded or centered, the justification mechanism is disabled by locking the justification bar 27 against upward thrust. Referring to Fig. 1, two locks 101 and 102 are provided to prevent both first and second justifications from taking place, a lock being provided for each of the justification rods because of the independent actuation of the rod 28 for first justification. In their active positions, the lock 101 is adapted to be located above the upper end of the collar 30 of the justification rod 28, and the lock

102 located above a block 103 carried by the justification rod 29. As shown, the lock 101 is formed at the end of the longer arm of a bell crank lever 104 pivoted to the vise frame as at 105, while the lock 102 is formed at the free end of a long lever 106 pivoted to the vise frame at 107. The two levers are connected by a link 108 to move in unison into and out of their active positions. The shorter arm 109 of the bell crank lever 104 is connected by an upright link 110 to a smaller bell crank lever 111, which in turn is connected by a link 112 to the handle 21 before referred to.

The arrangement of the parts is such that when the handle 21 is operated to couple the vertically movable rod 11 to the vise jaw operating levers 12 and 13 for a quadding or centering operation, the levers 104 and 106 will be rocked to locate the locks 101 and 102 in their active position, as shown by the full lines in the drawings, whereas when the handle is operated to uncouple the rod 11 from the vise jaw operating levers for a regular machine operation, the levers will be rocked to locate the locks in their inactive position, as indicated in part by the dotted lines in Figs. 4 and 5. It may be pointed out that a slight upward movement of the justification bar 27 is permitted before the locks 101 and 102 become effective, this being desirable if any spacebands happen to be present in the line because the bar will raise the long wedge sections thereof a slight amount sufficient to insure that their upper ends extend above the routing notches of the matrices and cut off any possible leakage of molten metal at this point during casting.

As a further feature of the invention, it is proposed to disable the locking mechanism for the vertically movable rod 11 during a regular machine operation, the idea being to avoid undue wear on the rack teeth formed on the rod and on the locking detents. This is accomplished, in the preferred embodiment illustrated, by the pivotal mounting previously referred to of the roller arm 58 (forming part of the pot actuated connections for the locking detents) upon the longer arm of the bell crank lever 104 carrying the lock 101 for the justification rod 28. Due to such mounting of the arm 58, it will be carried into and out of engaging relation to the spring plunger 59 carried by the pot leg, according to the conditioning of the machine. In other words, when the machine is conditioned for quadding or centering, as indicated by the full lines in the drawings, the roller arm 58 will be located directly in front of the plunger 59 and will transmit the rocking motion of the melting pot to the locking detents 40 to engage them with the vertically movable rod 11. On the other hand, when the machine is conditioned for a regular machine operation, the roller arm 58 will be shifted to the left out of engaging relation to the plunger 59 (see the dotted lines in Figs. 4 and 5) and thus fail to transmit the rocking motion of the melting pot to the locking detents, which consequently remain at rest and out of engagement with the rod. In this connection, it may be noted that, during the shifting movements of the arm 58, the roller 57 carried thereby will slide along the plate 56, which is made long enough for the purpose and which thus maintains the arm in proper position at all times.

The foregoing improvements have been shown merely by way of example and in preferred form. Many variations and modifications will be obvious to those skilled in the art and come within

the spirit of the invention as set forth in the appended claims.

Having thus described my invention, what I claim is:

5. 1. A slug casting machine equipped with aligning mechanism for the composed line and with a melting pot movable to and from casting position and including, in combination, a pair of line clamping jaws movable one toward the other in quadding, mechanism for effecting such quadding movement of the jaw, a locking device to hold the jaw in its line contacting position, and means independent of the jaw moving mechanism and actuated by the movement of the melting pot to casting position for effecting the engagement of the locking device after the aligning action has taken place.
- 10 2. In a slug casting machine equipped with aligning mechanism for the composed line and with a melting pot movable to and from casting position as well as with a transporter to carry the composed line to and from casting position and including, in combination, a pair of line clamping jaws movable one toward the other in quadding, mechanism for effecting such quadding movement of the jaw, a locking device to hold the jaw in its line contacting position, means independent of the jaw moving mechanism and actuated by the movement of the melting pot to casting position for effecting the engagement of the locking device after the aligning action has taken place, and means actuated by the movement of the line transporter from casting position for effecting the disengagement of the locking device.
- 15 3. A slug casting machine according to claim 1, including means for disabling the pot actuated means to render the locking device inactive during a regular machine operation.
- 20 4. A slug casting machine equipped with aligning mechanism for the composed line and with a melting pot movable to and from casting position and with justifying mechanism for expanding a composed line and including, in combination, a pair of line clamping jaws movable one toward the other in quadding, mechanism for effecting such quadding movement of the jaw, a locking device to hold the jaw in its line contacting position, means independent of the jaw moving mechanism and actuated by the movement of the melting pot to casting position for effecting the engagement of the locking device after the aligning action has taken place, means for locking the justifying mechanism to render it inoperative to expand the line when the latter is quadded, and common manually adjustable means for rendering the pot actuated means inactive and the justifying mechanism active during a regular machine operation.
- 25 5. In a slug casting machine equipped with a pair of line clamping jaws movable one toward the other in quadding, the combination of a vertically movable rod for effecting such quadding movement of the jaw, said rod being provided with a series of uniformly spaced rack teeth, a plurality of detents having correspondingly spaced rack teeth for locking the rod after movement to hold the jaw in its line contacting position, said detents having their teeth disposed in stepped relation to insure the engagement of one or another of the detents with the rod in minutely varying positions of the rod, a cage in which the locking detents are mounted and in which they are arranged horizontally one upon another in vertical stack formation but with
- 30
- 35
- 40
- 45
- 50
- 55
- 60
- 65

- 75

freedom of independent movement, a corresponding plurality of horizontally disposed spring-pressed plungers also mounted in the cage and which permit the detents to yield with reference to one another as one becomes operatively engaged with the rod, a relatively fixed housing in which the cage is slidably supported, said cage being slidable horizontally in opposite directions to effect the engagement and disengagement of the detents with and from the vertically movable rod and slideable vertically in opposite directions to apply opposite vertical thrusts to the detents while engaged with the rod; means for effecting such horizontal movements of the cage, and additional means for effecting such vertical movements of the cage.

6. The combination according to claim 5, wherein the means for effecting the horizontal sliding movements of the cage include a rotatable screw, said screw being threaded in the fixed housing and having a hub portion which is connected by a swivel to the cage.

7. In a slug casting machine equipped with a melting pot movable to and from casting position and with a pair of line clamping jaws movable one toward the other in quadding, the combination according to claim 6, wherein the means for effecting the horizontal sliding movements

15

20

25

of the cage include connections operated by the movement of the melting pot to casting position for rotating the screw in one direction.

8. In a slug casting machine equipped with a melting pot movable to and from casting position, a transporter for carrying the composed line to and from casting position, and a pair of line clamping jaws movable one toward the other in quadding, the combination according to claim 7, wherein the means for effecting the horizontal sliding movements of the cage include connections operated by the movement of the line transporter from casting position for rotating the screw in the opposite direction.

JOSEPH F. KRUSBERGER.
